UNITED STATES PATENT OFFICE.

JOHN T. MULROY, OF BROOKLYN, NEW YORK.

FIRE-FIGHTING APPLIANCE.

Application filed March 7, 1927. Serial No. 173,547.

This invention is an appliance adapted to be associated with a fire hose, to be used more particularly in the fighting of fires in buildings. Under the present method of fighting fires, it is the practice for firemen to carry a hose with an attached nozzle up a ladder to the window of the room or floor where the fire is in progress and stand upon the ladder at the window and direct the stream of water into the burning building. This is a very hazardous undertaking in many cases as flames and smoke not infrequently exit through the window at which the firemen are stationed causing them to be overcome and in many instances seriously injured.

It frequently occurs, moreover, that where the heat from the fire is intense and the firemen cannot gain access to the window by ladders, water towers are used or a stream of water is directed by firemen stationed in the street, or in adjoining buildings. When a stream of water is directed through a window from a distance, the stream within the building is localized and that proper distribution of the water throughout the enclosure is not obtained.

It is found that the best results in the extinguishing of fire within an enclosure are obtained by producing a maximum distribution of the water throughout the enclosure and for this reason firemen man the hose from window sills wherever circumstances will permit.

With these considerations in mind, the object of the present invention is to provide a device which may be attached to a window sill in an expeditious and simple manner by firemen and which after attachment may be left in place on the window sill to feed a stream of water with maximum distribution into an enclosure while the firemen withdraw from the danger zone leaving the apparatus to automatically function.

Speaking generally, the invention embodies a fire hose nozzle mounted for oscillation upon a suitable support and adapted to be oscillated by a stream of water fed through a hose to the nozzle so that, as the water issues from the nozzle, the nozzle will be oscillated to point in constantly varying directions in order to give a maximum distribution of the stream.

In the preferred practical form of the invention, the nozzle is mounted for oscillation upon the forward end of a hollow bar-

rel to the after end of which a fire hose is coupled. The barrel is mounted upon suitable clamping means adapted to engage a window sill, doorway or other part of a building to securely mount the device in place thereon.

Associated with the barrel is a member adapted to be rotated by the passage of water through the barrel and this member is operatively connected to the nozzle and forms a prime mover for effecting oscillatory movement of the nozzle. I find it convenient to employ a water wheel for this purpose and connect the water wheel through a crank movement to one arm of a bell crank, the other arm of which is secured to the nozzle and the elbow of which crank is secured by a stationary pivot to the barrel. Thus, as water flows through the barrel and rotates the water wheel, the crank movement results in oscillatory movement of the bell crank, which, in turn, effects an oscillatory movement of the nozzle. The nozzle may be associated with the barrel in any suitable manner, but it is found in practice that a ball and socket joint connection will function with high efficiency.

It is preferred, moreover, to so mount the barrel upon the clamp as to permit of rotation of the barrel upon its longitudinal axis and also for tilting movement with respect to the clamp, whereby the structure may be mounted on either a horizontal or vertical support and will provide for maximum distribution of the water.

Features of the invention, other than those specified, will be apparent from the herein-after detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a side elevation of a fire fighting appliance embodying this invention.

Figure 2 is a vertical section through the structure of Figure 1, this section being taken on the line 2-2 of Figure 3.

Figure 3 is a plan view of the construction of Figure 1; and,

Figure 4 is a transverse section taken on the line 4-4 of Figure 3.

Referring to the drawings, 1 designates a suitable supporting bed formed in one side

with a pair of rigid clamping jaws 2. The bed is provided with a longitudinal slideway 3 into which extends the tongue 4 of a movable clamping jaw 5. The tongue is adapted 5 for longitudinal adjustment within the slide-way and may be locked in any desired position by means of a thumb screw 6. The jaw 5 is fitted over a threaded shank 6^a on the tongue and a tapped handle 7 is screwed on 10 to the threaded shank and is adapted to operate directly against the movable jaw 5. By this arrangement, the supporting bed 1 may be readily and expeditiously secured to a window sill, shown in dotted lines in Figure 15 1. Variations in the widths of window sills is compensated for by proper adjustment of the tongue 4 when the set screw 6 is loosened.

During this adjustment, the handle 7 should be backed off from the tongue 5, but 20 after the adjustment of the tongue 4 has been accomplished and the thumb screw 6 tightened the handle may then be screwed up against the movable jaw to tightly grip the window sill. These operations may be 25 speedily accomplished and serve to mount the bed plate rigidly upon the window sill or upon the side of a doorway or on any other suitable and convenient support. If desired, the clamping means associated with 30 the supporting plate 1 may be of any other suitable form and may be adapted to clamp on to a pipe. The fundamental requisite is that the supporting bed be readily attachable to some fixed part of a building in order 35 to form a firm support for the operating parts superimposed thereon.

Mounted fixedly upon the support 1 is a bracket 8 through which is passed a spindle 9 and to the opposite ends of this spindle are 40 secured yokes 10. These yokes carry two split rings or collars 11, which encircle and support a barrel 12, as shown best in Figures 1 and 2. The rings fit loosely around the barrel so that the barrel is free for rotation 45 on its longitudinal axis and may be adjusted manually in any suitable manner. A thumb screw may be associated with one of the rings to lock the barrel against inadvertent rotation. As shown in the drawings, the barrel 50 is substantially cylindrical. It is provided at its rear end with a threaded boss 13 adapted to receive the coupling 14 of the fire hose 15.

At its forward end, the barrel is formed 55 with a club-like portion 16, with which the nozzle 17 cooperates. From Figure 2, it will be noted that the base of the nozzle is formed with a substantially semi-spherical portion 18 positioned within the globular 60 portion 16 and cooperating therewith after the manner of a ball and socket joint, so as to permit the nozzle to be oscillated with respect to the barrel without appreciable leakage of the joint between the barrel and 65 nozzle. In practice, this joint may be

ground, so that the parts will slide smoothly with respect to one another and without undue leakage. The pressure of the water will assist in maintaining a tight joint at this point. 70

The top of the barrel is formed with an elongated slot 19 and juxtaposed with this slot is a water wheel chamber 20 secured to the barrel by means of screws 21. A water wheel 22 is positioned within the chamber 75 and extends through the slot 21 into the interior of the barrel and into the path of water flowing therethrough whereby the flow of water results in rotation of the water wheel. The water wheel is mounted on the shaft 23 which extends through one side wall of the water wheel chamber and carries a crank 24. This crank is connected by means of a pitman 25 to one arm 26 of a bell crank, the other arm 27 of which is pivoted 85 to a bracket 28 secured to the nozzle. The bell crank is pivoted at its elbow on a thumb screw 29 which threads into the barrel or into a bearing plug associated therewith, so that the thumb screw 29 constitutes a fixed 90 pivot for the bell crank.

It will thus appear that when water is flowing through the barrel to the nozzle to be discharged from the latter, the flow of such water will operate the water wheel to 95 bring about oscillatory movement of the nozzle through the operative connections described and this oscillatory movement of the nozzle which is obviously entirely automatic will cause a stream of water flowing 100 from the nozzle to be discharged in constantly varying directions, so as to give a maximum distribution of such water.

When the appliance is associated with a horizontal window sill, the parts will be 105 positioned as substantially shown in Figure 1 and the barrel will be precluded from tilting on the spindle 9 by means of a detent 30. This detent is mounted on a bracket 31 secured to the supporting plate and is adapted 110 for pivotal movement. One end of the detent extends outwardly from the bracket and forms a finger piece 32, while the other end extends inwardly from the bracket and forms a locking finger which is adapted to 115 cooperate with notches 34 formed in an arcuate portion 35 of one of the yokes 10. A spring 36 is coiled around the pivot of the detent and normally forces the locking finger 120 into engagement with one of the notches 34. When it is desired to change the inclination of the barrel, the finger piece 32 is depressed to lift the locking finger from engagement with the notches and after the barrel has been adjusted to the desired 125 inclination the finger piece is released to permit the locking finger to engage with a contiguous notch, whereupon the barrel is again locked against inadvertent tilting 130 movement.

It will be apparent from the foregoing detailed description that the present invention embodies many features of novelty over prior fighting apparatus. The appliance 5 may be readily attached to a fire hose fed from a high pressure main or from the fire engine and is sufficiently light to be easily carried up a ladder to be attached to a window, doorway or other part of the building. I wish to call particular attention to the fact that the water has a substantially straight-through passage through the appliance and is not required to turn sharp corners or to appreciably change direction 10 during such passage.

Experience has shown that where the water is required to turn sharp corners, the pressure is materially decreased and the ability to throw a stream is pronouncedly 15 less than when a straight-through passage is provided. As a matter of fact, if the device was so constructed that the water had to turn relatively sharp corners or change direction at relatively sharp angles, the device 20 would be practically useless for the purposes specified. Actual experience has proven this to be a fact.

Attention is further called to the fact that the water wheel does not extend to any 25 appreciable distance into the barrel and consequently into the flow of the water and does not therefore seriously interfere with the passage of such water. In other words, the water has a substantially uninterrupted 30 flow through the device and the paddle wheel is positioned off to one side, so as not to interrupt this flow. No great amount of power is required to operate the water wheel, and, in practice, it affords very little 35 if any retardation of the current.

The device may be expeditiously and easily mounted on a part of a building by the manipulation of a handle and thumb screw and will be firmly held in place when thus 40 attached. The inclination of the barrel may be expeditiously adjusted by the detent 45 as described and the barrel may be rotated within the collars 11 as circumstances may require.

Ordinarily the thumb screw 29 is sufficiently loose to permit oscillation of the nozzle under the impulse of the water wheel, although if it is desired to lock the nozzle 50 against oscillation, the thumb screw 29 may 55 be screwed down tight and will produce suf-

ficient friction between the bell crank and the barrel to preclude movement of the nozzle by the water wheel. The device is simple in construction, may be economically manufactured, is relatively light and thoroughly 60 efficient in the carrying out of its intended functions.

In the foregoing detailed description, I have described the preferred embodiment of the invention. I wish it understood, however, that other forms of supporting base and clamp may be employed without departing from this invention. Other mechanical changes will be apparent to those skilled in the art after reading the foregoing detailed 65 description and the invention is therefore to be understood as fully commensurate with the appended claims.

Having thus fully described the invention, what I claim as new and desire to secure by 70 Letters Patent is:

1. In a fire fighting apparatus, a hollow casing provided with a water inlet, a water wheel projecting into the casing and adapted to be rotated by water passing through the 80 casing, a nozzle flexibly connected with said casing and axially aligned therewith, and means connecting said water wheel and nozzle for imparting oscillations to the nozzle.

2. In a fire fighting apparatus, a hollow 85 casing provided with a water inlet, a water wheel projecting into the casing and adapted to be rotated by water passing through the casing, a nozzle flexibly connected with said casing and axially aligned therewith, means 90 connecting said water wheel and nozzle for imparting oscillations to said nozzle, and means for supporting said casing in adjustable positions.

3. In a fire fighting apparatus, a hollow 95 casing provided with a water inlet, a water wheel projecting into the casing and adapted to be rotated by water passing through the casing, a nozzle flexibly connected with said casing and axially aligned therewith, means 100 connecting said water wheel and nozzle, for imparting oscillations to said nozzle, means for supporting said casing in adjustable positions, said connecting means comprising bell crank and lever connections between the 105 water wheel and nozzle.

In testimony whereof I have signed the foregoing specification.

JOHN T. MULROY.
